PACKAGE AND METHOD OF MAKING SAME

Leroy L. Salfisberg, South Orange, N. J.

Application December 10, 1931, Serial No. 580,116

6 Claims. (Cl. 206—56)

The present invention relates to an improvement in packages and method of making the same, and finds application more particularly to the packaging of products such as medicinal or chemical preparations, edible articles in tablet or similar form, articles of hardware, buttons and/or other relatively small articles.

In some respects this invention constitutes an improvement over the invention described and claimed in my Patent No. 1,413,064 dated April 18th, 1922, wherein I have described a package in which the articles are carried in compartments separated by crimped sealing portions, the packaging material being of paper having a coating of paraffin.

An object of the present invention has been to provide a package which embodies some of the advantages and desirable qualities of the package described and claimed in my patent aforementioned as well as other novel features permitting effective use of transparent cellulose as the packaging material, and a method of making such a package.

One difficulty in the use of packages made of transparent coated cellulose having properties otherwise suitable for the purpose is its relative toughness or resistance to tearing which prevents ready access to or removal of the contents. To obviate this difficulty, I provide a package wherein in different portions of the walls have different characteristics or degrees of toughness. For example, those portions of the walls which engage the packaged contents or which form the compartment or space in which the packaged articles are confined, retain the normal toughness of the material; whereas other portions of the walls, namely those which are pressed together to define or close the article containing space are relatively more brittle than the first mentioned portions.

A further object of my invention has been to provide a method of making a package having these features of construction. For this purpose, I preferably employ transparent cellulose sheet material provided with a fusible coating to form the walls of my package. When heat is applied to portions thereof in sufficient amount, said coating is melted or fused and embrittlement of the underlying cellulose substance occurs. Interior surfaces of said heated portions of the walls are pressed into adhering contact to define or close the contents receiving compartment or space above referred to.

In the drawing accompanying the present specification, I have illustrated a preferred form of

package embodying my invention and also have shown portions of apparatus in connection with the use of which my improved method may be effectively practiced. In this drawing:

Figure 1 is a plan view of a portion of a strip of transparent cellulose with articles arranged thereon in position to be packaged;

Figure 2, a plan view of a portion of a completed package;

Figure 3, a longitudinal section of a portion of a package;

Figure 4, a transverse section on the line 4—4 of Figure 3;

Figure 5, a transverse section on the line 5—5 of Figure 3;

Figure 6, a schematic side elevation of apparatus for longitudinally sealing and for forming transversely separated compartments; and

Figures 7 and 8 are detail views in perspective, illustrating cutting or punching devices for reducing the cross sectional area of the compartment separating portions of the package.

In making one type of package according to the method forming a part of my present invention a strip 1 of transparent cellulose or like transparent flexible material having a fusible coating of transparent substance, such for example as that described in United States patent to Charch and Prindle, No. 1,737,187, is folded longitudinally to form in effect a tubular container 25 with its inner surface coated adapted to enclose spaced articles 2 either with or without a marker or insert 14. Devices for folding strips of this type are shown in the patent to C. H. McDonald, 1,531,804. In connection therewith I employ 30 suitable sealing or tube forming mechanism whereby the folded over or overlapping edges of the package forming strip are sealed together longitudinally. For this purpose, I provide a sealing roller 3, co-operating with a platen 4, 35 said roller, or peripheral portions thereof, being heated by any suitable means, such as a resistance element 5, connected by conductors with a source of electrical energy, not shown. The platen 4 is supported to extend in the direction 45 of movement of the strip 1 and underlies folded over portions thereof in such a manner that, when the heated roller 3 is pressed downwardly against the upper folded over portion or layer, the overlapping portions or layers are pressed 50 together and subjected to heat at the same time. This fuses or melts the coating of the heated and pressed together parts and forms a closure or sealing represented at 6, Figures 4 and 5, extending longitudinally of the tube.

The patent to McDonald also illustrates crimping devices in advance of the folding devices. For the purposes of my invention, insofar as it involves closing or defining the article receiving space and treating portions of the package walls to render them more easily tearable in use, I supply means for heating the crimping or pressing dies 7 of the rollers 8, said heating devices being preferably resistance elements 9 suitably insulated and connected with sources of electrical energy not shown. The application of a suitable amount of heat and pressure to said portions of the layers or walls of the package by means of the dies 7 produces melting or fusing of the coating of opposed interior surfaces of said portions and the pressing together of said fused surfaces into adhering contact. A further effect of heating portions of the walls by said dies is a localized chemical or physiochemical change in structure of the package material whereby said heated portions after cooling are relatively more brittle and more readily torn than the unheated portions.

Another way of weakening the cross section of the illustrated type of package at the transversely sealed or adhering portions is to provide opposed notches 10 and 11, Figure 2, formed by punching out or cutting away portions of the adhering walls. For this purpose, one of the dies 7 is provided with recesses 12 which co-operate with projections 13, Figures 7 and 8, to form a punch or cutter whereby, when the package forming tube passes between the dies 7, portions of the material of the compartment separating or adhering parts of the package walls are punched out or cut away.

In cases where it is desirable to incorporate with the packaged articles a suitable marking to indicate origin, to identify the contents, or for some other purpose, I provide an insert or marker in the form of a strip as 14, preferably of relatively opaque material or bearing markings 15 arranged to be visible through the walls of the compartments. As shown in Figure 6, the insert 14 is conveniently incorporated in the package simultaneously with the article depositing and strip folding operations, as shown in Figure 5, portions of the marking strip are secured between the opposed crimped or pressed together walls of the tube, so that the marker remains in substantially fixed relation to the compartment walls.

It will be understood, in connection with the above description of apparatus for producing a package embodying my invention and for practicing my improved method, that the showing of resistance elements is merely diagrammatic, it being contemplated that such devices will preferably be designed and located to meet the special requirements of various kinds of packages, or to co-operate, as an attachment, with various types of folding and/or crimping or pressing instrumentalities.

I claim:—

65 1. In the method of commodity packaging uti-

lizing coated flexible regenerated cellulose material of an essentially wiry nature, the step of partial oxidization for forming bonding areas of a different nature in said material for promoting susceptibility to tearing for removal of the packaged commodity which comprises heating a restricted area of said coated material to an extent greater than that required to produce the mere adherence of said packaging material with another portion of packaging material but to an extent less than that which would cause the crumbling of the material, whereby a package is produced utilizing the essential wiry nature of said material in a commodity retaining area while utilizing an embrittled bonded area adjacent said retaining area as an integral seal susceptible to facile tearing for ready access to the commodity retaining area for removal of the commodity therefrom.

2. A package in the form of a commodity enclosing sheath comprising regenerated cellulose packaging material of an essentially wiry nature and having a coated area of said packaging material joined in bond with another portion of packaging material adjacent said commodity enclosure, said area of bond of said packaging material being of an oxidized brittle nature whereby said package utilizes the normally wiry nature of said packaging material for the commodity enclosing area and utilizes said brittle area of bond as a seal for said enclosing area susceptible to facile tearing for ready access to the commodity retaining area to permit removal of the commodity therefrom.

3. A package composed of opposed layers of regenerated cellulose of an essentially wiry nature joined together in restricted areas in an inseparable and embrittled bond, differing in tearing characteristics from said normal wiry nature of said material, as distinguished from a separable adhering bond, to form a seal joining said layers in a commodity containing enclosure composed of said other areas of said layers of said wiry nature, said bond being susceptible to facile tearing for permitting ready access to the commodity retaining enclosure formed by the areas of material of a nature relatively more resistive to tearing.

4. A package in accordance with claim 3 in which said layers are interdigitated in said bond.

5. A package comprising a plurality of commodity containing envelopes of flexible regenerated cellulose packaging material of an essentially wiry nature inter-joined by sealing areas of packaging material of a different physiochemical nature less resistive to tearing and of an oxidized embrittled nature whereby said package utilizes the wiry nature of said material in said containing envelopes for commodity retaining purposes and utilizes said embrittled sealing areas of said material to permit facile separation of said envelopes.

6. A package in accordance with claim 5 in which said sealing areas have portions of reduced dimensions to further facilitate tearing at said areas.
